US00D964668S

(12) **United States Design Patent** (10) Patent No.: **US D964,668 S**
(45) Date of Patent: **** Sep. 20, 2022**

(54) **WIRELESS REMOTE CONTROL DOG TRAINING DEVICE**

(71) Applicant: **Shenzhen Smart Pet Technology Co., Ltd**, Shenzhen (CN)

(72) Inventor: **Yaya Jia**, Shenzhen (CN)

(73) Assignee: **Shenzhen Smart Pet Technology Co., Ltd**, Shenzhen (CN)

(**) Term: **15 Years**

(21) Appl. No.: **29/832,552**

(22) Filed: **Mar. 29, 2022**

(51) LOC (13) Cl. **30-99**

(52) U.S. Cl.

USPC **D30/199; D10/104.1**

(57) **CLAIM**

The ornamental design for a Wireless remote control dog training device, as shown and described.

DESCRIPTION

FIG. 1 is a perspective view of a wireless remote control dog training device showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines depict portions of the wireless remote control dog training device and form no part of the claimed design.
